CLAIM

The ornamental design for a bottle with pump and handle, as shown and described.

DESCRIPTION

FIG. 1 is a perspective view of a bottle with pump and handle, embodying my new design;

FIG. 2 is a back elevational view thereof;

FIG. 3 is a front elevational view thereof;

FIG. 4 is a side elevational view thereof; and the opposite side elevational view thereof being the same;

FIG. 5 is a top view thereof; and,

FIG. 6 is a bottom view thereof.
